Primary Examiner — Mary Ann Calabrese*Assistant Examiner* — Harper E Comstock(74) Attorney, Agent, or Firm — Steven A. Nielsen; www.NielsenPatents.com(57) CLAIM

The ornamental design for a towel, as shown and described.

DESCRIPTION

FIG. 1 is a top view of a towel showing my new design; and, FIG. 2 is a bottom view thereof.

The broken lines represent features of the towel that form no part of the claimed design.
